UNITED STATES PATENT OFFICE

ALBERT L. ABBOTT, OF CANTON, OHIO, ASSIGNOR TO DIEBOLD SAFE & LOCK COMPANY,
OF CANTON, OHIO, A CORPORATION OF OHIO

SAFE

Application filed October 8, 1929. Serial No. 398,157.

My invention relates to safes, and more particularly to safes made of sheet metal and heat resisting material, and adapted for the protection of valuables, documents, records, 5 and the like, against the usual hazards and particularly against the hazards of fires, explosions and of combined fires and explosions.

Safes for this purpose should be built to 10 withstand and endure with a substantial margin of safety, separately or simultaneously, the hazards of impact, crushing loads, and falls, and of long periods of intense heat.

15 Considerable difficulty has been encountered in making a structure having the capacity to withstand all of these hazards.

Safes have been made including an inner main frame made of structural shapes 20 rounding and maintaining a compartment in which are placed the valuables, documents, records, and the like to be protected, the main frame and compartment being themselves surrounded by a combined heat and 25 compression resisting monolithic shell, and the compartment, main frame and monolithic shell all being surrounded by an external sheet metal case.

Such a safe structure is adequate from the 30 standpoint of strength, but is relatively costly to manufacture. As aforesaid, the several parts thereof include two classes of materials, structural shapes and sheet metal, thus necessitating for each class, the special 35 equipment and special labor necessary for working that class of material.

The objects of the present improvements include the provision of a safe which, except 40 for hardware and fittings, may be made entirely of sheet metal and heat resisting material, and which at the same time shall meet the requirements as to strength and resistance to fire, heat and explosion, whereby a single class of material and labor may be 45 used, less weight of material are required, and manufacturing economies thereby effected.

These and other objects are attained by 50 the use of an inside compartment in which are placed the valuables, documents, records,

and the like to be protected, the compartment walls being preferably made of panels comprising spaced metal sheets and the metal sheets at sides of each panel being formed and positioned for overlapping with the metal sheets at sides of the other panels to form at the corners of the compartment a main structural frame the members of which are preferably W-shaped in cross section and are laminated by reason of the overlapping of the metal sheets, and are positioned with respect to the external case in such manner as to permit the use of a maximum amount of heat and fire resisting material in the monolithic shell at the corners. 55

A preferred embodiment of the invention is illustrated in the accompanying drawings forming part hereof, in which

Figure 1 is a fragmentary vertical cross section of one of the improved safes, as on 60 line 1—1, Fig. 2;

Fig. 2, a fragmentary horizontal cross section of the same, as on line 2—2, Fig. 1; and

Fig. 3, a fragmentary perspective view illustrating the manner of overlapping and joining the panel sides to form the laminated 65 main frame.

Similar numerals refer to similar parts throughout the several views.

The improved safe indicated generally at 80 10, includes panels forming a novel five-walled inner compartment indicated generally at 11, a five-walled monolithic heat and fire resisting shell indicated generally at 12, the shell being provided with tension reinforcing means indicated generally at 13, and the compartment and shell being enclosed in an external five-walled interlocking case indicated generally at 14. 85

A door frame indicated generally at 15 90 connects the opening of the inner compartment 11 with the opening of the outer case 14, and forms a closure for the outer end of the monolithic shell 13.

A door indicated generally at 16 is 95 mounted at one side by hinges 17 upon the outer case, and provides a closure fitting in the open sixth sides of the case and compartment.

The door preferably includes an outer shell 100

18 of metal sheets, the interior of which is filled with heat resisting material 19 and tension reinforcing 20.

The outer shell may be constructed of 5 metal sheets in general according to the disclosure of the prior patent of Bruno T. Gialdini, No. 1,826,768, issued Oct. 13, 1931.

The novel inner compartment 11 is formed by five panels: namely, a top panel 21a, a 10 bottom panel 21b, side panels 21c and 21d, and a back panel 21e.

Each of the panels includes spaced sheets formed and secured to each other and comprising a box including outwardly extending 15 flanges which may be straight or L shaped and notched as required.

The top panel 21a includes an inner formed plate or sheet 22a and an outer formed plate or sheet 23a.

20 The central portion 24a of the outer sheet 23a is rectangular and is parallel with and spaced from the inner sheet 22a. Each side of the outer sheet 23a is formed in the shape of an L flange 25a and includes an outer leg strip 26a parallel with the central portion and spaced therefrom for abutment against the inner sheet 22a, and a connecting leg strip 27a extends between the inner edge of the strip 26a and the outer edge of the central portion 24a.

25 The outer leg strips 26a are abutted against the inner sheet 22a and are secured thereto as by spot welding, thus forming a box having outwardly extending flanges formed by the abutting outer leg strips and the outer side portions of the inner sheet.

30 For reinforcing the box, Z members 28a are located between the inner and outer sheets 22a and 23a, and each Z member is 40 preferably formed of sheet metal and includes oppositely extending inner and outer flanges 29a and 30a connected by a web 31a, the inner flange 29a being secured as by spot welding to the inner sheet 22a and the outer flange 30a being secured as by spot welding to the outer sheet 23a.

35 For purposes to be hereinafter set forth in detail, two opposite sides of the inner plate 22a are provided with downwardly extending flanges 32a, and the downwardly extending flanges are notched at 33a at their rear ends.

40 The bottom panel 21b includes an inner formed plate or sheet 22b and an outer formed plate or sheet 23b.

45 The central portion 24b of the outer sheet 23b is rectangular and is parallel with and spaced from the inner sheet 22b. Each side 50 of the outer sheet 23b is formed in the shape of an L flange 25b and includes an outer leg strip 26b parallel with the central portion and spaced therefrom for abutment against the inner sheet 22b, and a connecting leg strip 27b extends between the inner edge of

the strip 26b and the outer edge of the central portion 24b.

The outer leg strips 26b are abutted against the inner sheet 22b and are secured thereto as by spot welding, thus forming a box having 70 outwardly extending flanges formed by the abutting outer leg strips and the outer side portions of the inner sheet.

75 For reinforcing the box, Z members 28b are located between the inner and outer sheets 22b and 23b, and each Z member is preferably formed of sheet metal and includes oppositely extending inner and outer flanges 29b and 30b connected by a web 31b, the inner flange 29b being secured as by spot welding 80 to the inner sheet 22b and the outer flange 30b being secured as by spot welding to the outer sheet 23b.

85 For purposes to be hereinafter set forth in detail, two opposite sides of the inner plate 22b are provided with upwardly extending flanges 32b, and the upwardly extending flanges are notched at 33b at their rear ends.

90 The side panel 21c includes an inner plate or sheet 22c and an outer formed plate or sheet 23c.

95 The central portion 24c of the outer sheet 23c is rectangular and is parallel with and spaced from the inner sheet 22c. Each side of the outer sheet 23c is formed in the shape of an L flange 25c and includes an outer leg strip 26c parallel with the central portion and spaced therefrom for abutment against the inner sheet 22c, and a connecting leg strip 27c extends between the inner edge of the strip 26c and the outer edge of the central portion 24c.

100 The outer leg strips 26c are abutted against the inner sheet 22c and are secured thereto as by spot welding, thus forming a box having 105 outwardly extending flanges formed by the abutting outer leg strips and the outer side portions of the inner sheet.

110 For reinforcing the box, Z members 28c are located between the inner and outer sheets 22c and 23c, and each Z member is preferably formed of sheet metal and includes oppositely extending inner and outer flanges 29c and 30c connected by a web 31c, the inner flange 29c being secured as by spot welding 115 to the inner sheet 22c and the outer flange 30c being secured as by spot welding to the outer sheet 23c.

120 The side panel 21d includes an inner plate or sheet 22d and an outer formed plate or sheet 23d.

125 The central portion 24d of the outer sheet 23d is rectangular and is parallel with and spaced from the inner sheet 22d. Each side of the outer sheet 23d is formed in the shape of an L flange 25d and includes an outer leg strip 26d parallel with the central portion and spaced therefrom for abutment against the inner sheet 22d, and a connecting leg strip 27d extends between the inner edge of 130

the strip 26d and the outer edge of the central portion 24d.

The outer leg strips 26d are abutted against the inner sheet 22d and are secured thereto as by spot welding, thus forming a box having outwardly extending flanges formed by the abutting outer leg strips and the outer side portions of the inner sheet.

For reinforcing the box, Z members 28d are located between the inner and outer sheets 22d and 23d, and each Z member is preferably formed of sheet metal and includes oppositely extending inner and outer flanges 29d and 30d connected by a web 31d, the inner flange 29d being secured as by spot welding to the inner sheet 22d and the outer flange 30d being secured as by spot welding to the outer sheet 23d.

The back panel 21e includes an inner formed plate or sheet 22e and an outer formed plate or sheet 23e.

The central portion 24e of the outer sheet 23e is rectangular and is parallel with and spaced from the inner sheet 22e. Each side 25 of the outer sheet 23e is formed in the shape of an L flange 25e and includes an outer leg strip 26e parallel with the central portion and spaced therefrom for abutment against the inner sheet 22e, and a connecting leg strip 27e extends between the inner edge of the strip 26e and the outer edge of the central portion 24e.

The outer leg strips 26e are abutted against the inner sheet 22e and are secured thereto as by spot welding, thus forming a box having outwardly extending flanges formed by the abutting outer leg strips and the outer side portions of the inner sheet.

For reinforcing the box, Z members 28e are located between the inner and outer sheets 22e and 23e, and each Z member is preferably formed of sheet metal and includes oppositely extending inner and outer flanges 29e and 30e connected by a web 31e, the inner flange 29e being secured as by spot welding to the inner sheet 22e and the outer flange 30e being secured as by spot welding to the outer sheet 23e.

For purposes to be hereinafter set forth in detail, each side of the inner plate 22e is provided with a forwardly extending flange 32e.

The downwardly extending flanges 32a at the sides of the inner plate 22a of the top panel 21a, overlap the upper outer leg strips or flanges 26c and 26d and the upper outer abutting portions or flanges of the plates 22c and 22d of the side panels 21c and 21d, and the overlapping flanges are secured to each other as by spot welding, thus forming at each front to rear extending side corners of the compartment, laminated members of a main rectangular frame for the compartment, and each of the laminated members

has a W cross section as is illustrated in Fig. 3.

Similarly, laminated front to rear side corner members of the main frame for the compartment are formed by the side flanges 32b of the bottom panel 21b overlapping and being secured, as by spot welding, to the bottom outer leg strips or flanges 26c and 26d and the lower outer abutting portions or flanges of the side panels 21c and 21d, as is illustrated in Fig. 3.

In a similar manner the rear laminated main frame corner members are formed for the compartment, as is illustrated in Figs. 1 and 2, by the forwardly extending flanges 32e of the back panel 21e overlapping and being secured, as by spot welding, to the rear and outer leg strips or flanges 26a, 26b, 26c, and 26d and the rear outer abutting portions or flanges of the inner plates 22a, 22b, 22c, and 22d.

The notches 33a in the side flanges 32a and the notches 33b in the side flanges 32b are provided to accommodate the overlapping of the flanges 32e.

The laminated W main frame corner members thus formed, are indicated at W in each corner, and in each corner the W corner member opens towards a corner of the outer case, whereby a maximum quantity of the heat and fire resisting material forming the monolithic shell 12, may be interposed between the corners of the inner compartment 11 and the outer shell 12, it being understood that the corners of the several shells or cases are subject to the maximum action of heat or fire.

I claim:

In a safe having an outer sheet metal housing and an integral monolithic wall structure, one of said walls having a door opening therein, the combination of a plurality of panels forming an inner compartment, each of said panels comprising outer and inner sheets, the inner sheets having their marginal portions secured to each other, and the outer sheets having the major portions thereof spaced from the inner sheets and extending parallel thereto, said outer sheets having flanges secured to said inner sheets, and sheet metal reinforcing members extending between the outer and inner sheets.

In testimony that I claim the above, I have hereunto subscribed my name.

ALBERT L. ABBOTT. 120
